ROLLER SKATE

Daniel S. Williams, Pottstown, Pa.

Application February 12, 1959, Serial No. 54,588

Term of patent 14 years

(Cl. D34—14)

The figure is a perspective view illustrating the design of a roller skate.

The opposite side of the skate is a duplicate of the side shown.

I claim:

The ornamental design for a roller skate, as shown and described.
